(21) Appl. No.: **29/152,816**

(57) **CLAIM**

(22) Filed: **Dec. 28, 2001**

The ornamental design for a hand-held electronic stamper,
as shown and described.

(51) **LOC (7) Cl. 19-02**

DESCRIPTION

(52) **U.S. Cl. D18/14**

FIG. 1 is a front elevational view of the hand-held electronic
stamper of the present invention;

(58) **Field of Search** D18/14, 15, 18,
D18/19, 21, 56; 400/692, 691, 679, 613,
613.1; 347/222, 263, 245; 118/256, 257;
101/103, 106, 327, 368, 371, 405, 406

FIG. 2 is a rear elevational view of the hand-held electronic
stamper of FIG. 1; and
FIG. 3 is a left side elevational view of the hand-held
electronic stamper of FIG. 1, the right view being a mirror
image thereof;

(56) **References Cited**

FIG. 4 is a top plan view of the hand-held electronic stamper
of FIG. 1;
